UNITED STATES PATENT OFFICE.

ROBERT H. VAN SANT, OF CHICAGO, ILLINOIS.

TOOTHBUSH.

Application filed May 23, 1925. Serial No. 32,239.

This invention relates to a tooth brush and the method of manufacture thereof.

It is an object of this invention to provide an improved tooth brush wherein a series of suction and force cups are formed with central groups of bristles adapted to dislodge foreign matter from crevices and the spaces between the teeth while the fluid pumping action of the cups serves to discharge the dislodged particles from the crevices.

It is also an object of this invention to provide improved tooth brushes of the type mentioned wherein a sheath of suitable material forming the cups is disposed upon a handle in such a way as to provide a unitary closure for that part of the brush proper entering the mouth.

It is a further object of this invention to provide a novel method of manufacturing tooth brushes of the class described.

Other and further important objects of this invention will be apparent from the disclosures in the specification and the accompanying drawings.

This invention (in a preferred form) is illustrated in the drawings and hereinafter more fully described.

On the drawings:

Figure 1 is a side view of a completed tooth brush embodying the features of this invention.

Figure 2 is a top plan view thereof.

Figure 3 is an enlarged longitudinal section of the brush end taken on the line III-III of Figure 2.

Figure 4 is an enlarged cross-section on the line IV-IV of Figure 1.

Figure 5 is a plan view of a modified form of this invention.

As shown on the drawings:

A tooth brush handle 10 of conventional shape is shown in the drawings, the brush end 11 thereof being of reduced section having a series of medial recesses 12 to receive bunches of bristles. The handle as a whole may be molded from a variety of materials such as celluloid, rubber, or one of the many phenol condensation products. While it is advantageous from the consumer's point of view to use a more or less flexible material for the handle such use is not essential.

The brush proper comprises a sheath 13 fitting over the reduced section 11 of the handle and carrying a series of deep suction

cups 14 each cup being alinged with one of the recesses 12 provided in the reduced section 11 of the handle. The sheath is preferably molded of a flexible or soft grade of rubber or the like, in order that the cups may have a squeegee action and conform to the irregular outlines of the teeth. Single clamps of bristles 15 are inserted through the bottom of each cup 14 into the recesses 12 of the handle, each clamp being centrally disposed in a cup and extending upwardly to the plane of the rim thereof.

The preferred method of manufacturing the tooth brush of this invention is to mold the handle 10, with the recesses 12 in the reduced section 11 thereof and to separately mold the much softer brush section or sheath with suitable apertures adapted to register with the handle recesses 12 when the sheath is slipped thereover. After assembling the sheath on the handle a ferrule 16 is placed thereon at the junction with the enlarged handle. The bristles are then cemented into place in the cups and handle. If desired the sheath may be molded directly on the handle with the bristles already in place; or the bristles inserted after molding to prevent possible injury thereto by the vulcanizing process.

The cupped members 15 serve as a squeegee or scraper for removing foreign matter from the teeth and gums and also as force and vacuum cups to pump cleansing fluid back and forth between the teeth, the bristles entering the crevices and dislodging foreign matter which is ejected by the pumping action of the cups.

The modification shown in Figure 5 comprises a handle 17 having a single row of bristles 18 arranged thereon, together with a single elongated cup 19 enclosing all the bristles. The rim 20 of the cup has a scraping action similar to the rims of the individual cups 15.

I am aware that many changes may be made and numerous details of construction may be varied through a wide range without departing from the principles of this invention, and I therefore do not purpose limiting the patent granted hereon, otherwise than necessitated by the prior art.

I claim as my invention:

1. As an article of manufacture a tooth brush comprising a handle, an encompassing sheath of resilient character forming the

brush portion, and groups of bristles projecting through said sheath into the handle.

2. As an article of manufacture a tooth brush comprising a handle having a brush receiving section, a sheath encompassing said section, suction cups formed on said sheath, and bristles centrally disposed in said cups.

3. A toothbrush comprising a handle having a brush receiving element, a soft rubber

sheath adapted to slip over said element, a ferrule clamping the end of said sheath to the handle, a series of suction cups formed on said sheath, and a group of bristles centrally disposed in each cup and extending through the sheath into the brush receiving element. ¹⁵

In testimony whereof I have hereunto subscribed by name.

ROBERT H. VAN SANT.
